UNITED STATES PATENT OFFICE.

CHARLES A. WITHERS, OF AUGUSTA, GEORGIA, ASSIGNOR TO INTERNATIONAL VENTILATOR AND DEFLECTOR COMPANY, OF WASHINGTON, DISTRICT OF COLUMBIA, A CORPORATION OF THE DISTRICT OF COLUMBIA.

SHIP'S COWL.

SPECIFICATION forming part of Letters Patent No. 761,620, dated May 31, 1904.

Application filed May 22, 1903. Serial No. 158,366. (No model.)

To all whom it may concern:

Be it known that I, CHARLES A. WITHERS, a citizen of the United States, residing at Augusta, in the county of Richmond and State of Georgia, have invented new and useful Improvements in Ships' Cowls, of which the following is a specification.

This invention relates to certain new and useful improvements in ships' cowls, and aims particularly to construct a ship's cowl provided with means whereby an induced upward current of air may be created in the conduit or conduits leading from the various apartments in the vessel through which the foul, vitiated, and heated air within the vessel may be withdrawn.

The usual method of ventilating ships is to provide a series of funnel-mouthed cowls projecting above the deck and communicating with passages or conduits which lead down into the various apartments within the vessel. The mouths of these cowls are directed toward the wind or toward the bow of the vessel, so that the draft or current of air is forced down into the vessel beneath the deck. An objection has arisen, however, to this method of ventilating in that while it provides for the introduction of fresh air it does not provide for the positive withdrawal of the foul or vitiated air. This objection is overcome by the new and improved construction of ship's cowl to be hereinafter referred to and which when set up is adapted to have its mouth directed in an opposite direction to the wind and surrounding the mouth of the cowl with a collar which, in connection with the cowl, forms an air-passage, the collar being so constructed and arranged as to have its forward end extend toward the bow of the vessel and its rear end toward the stern of the vessel and project over the mouth of the cowl, the collar being a flaring one or in the form of a truncated cone, so that the walls of the air-passage will be tapering and the inner end of the air-passage contracted. By this arrangement during the movement of the vessel a current of air will be forced through the air-passage formed by the collar and cowl and be directed

across the mouth of the cowl, which action induces a current of air upwardly through the cowl, with the result that an upward draft is produced through the cowl which withdraws the foul, vitiated, or heated air from the apartment or apartments with which the cowl communicates. The cowl may further be provided in its side with an opening, with which communicates a funnel for directing the air into the cowl, which assists in also forming an updraft, owing to the fact that the cowl is provided with a deflector with which the air contacts and is deflected upwardly through the cowl.

The invention further aims to construct a ship's cowl which shall be extremely simple in its construction, strong, durable, efficient in its use, one that can be used for an intake and an outtake of air, and comparatively inexpensive to manufacture.

With the foregoing and other objects in view the invention consists of the novel combination and arrangement of parts hereinafter more specifically described, illustrated in the accompanying drawings, and particularly pointed out in the claims hereunto appended.

In describing the invention in detail reference is had to the accompanying drawings, forming a part of this specification, wherein like reference characters denote corresponding parts throughout the several views, and in which—

Figure 1 is a vertical sectional view of my improved ship's cowl; Fig. 2, a rear elevation; Fig. 3, a vertical section of a modified form, and Fig. 4 a detail of the deflector.

On the upper end of each of the pipes or conduits 1 which lead down to and communicate with the various apartments within the vessel is adapted to be located a cowl 2, constructed in accordance with this invention. The cowl 2 is constructed with a cylindrical lower end 3 to permit of the attachment to the pipe or conduit 1 and the enlarging upper section 4, which forms the elliptical-shaped mouth 5 of the cowl, the upper section 4 of the cowl being of the ordinary construction. Surrounding the upper end of the section 4

of the cowl is a collar 6 substantially in the form of a truncated cone, and the collar 6 is connected to the section 4 by means of the short connecting- rods 7. Two or more of 5 these rods may be employed, if desired; but for example three are shown. The upper portion of the collar 6 is of greater width than the lower portion and gradually increases in width from its lower portion to its upper portion. 10 The collar 6 projects inwardly at an inclination and the upper portion thereof extends at a greater inclination than the lower portion. The upper portion of the collar projects over and away from the mouth of the 15 upper section 4. The collar 6, in connection with the section 4, forms an air-passage 8, and owing to the inward inclination of the collar 6 the outlet end of the passage 8 is contracted. Owing to the inward inclination of the collar 20 6 the air is deflected across the mouth of the cowl, so that such action induces a current of air upwardly through the conduit 1 and the cowl, with the result that an upward draft is produced through the conduit 1 and cowl 2, 25 which withdraws the foul, vitiated, or heated air from the apartment or apartments with which the conduit 1 communicates. The position of the cowl 2 when set up to obtain the 30 operation just specified is that the mouth thereof is directed away from the wind, so that a draft or current of air will be forced through the air-passage formed by the collar 6 and the section 4 and be discharged at the contracted inner or outer end of the passage. 35 In the modified form of cowl shown in Fig. 3 the construction of the upper portion of the cowl is the same as that shown in Figs. 1 and 2, the same reference characters being applied thereto, and it is thought unnecessary to refer 40 to these parts again. The difference which exists between the modified form shown in Fig. 3 and the construction shown by Figs. 1 and 2 is that the cylindrical portion 3 of the cowl is provided with an opening 9, with which 45 communicates an air-passage formed by the funnel 10, which is secured to the cylindrical portion 3 of the cowl around the opening 9. Within the cylindrical portion 3 of the cowl is arranged a diamond-shaped deflector 11 in 50 suitable relation to the opening 9, so that as the air enters the cylindrical portion of the cowl through the opening 9 it will be deflected upwardly by the diamond-shaped deflector 11 and will induce a current of air upwardly 55 through the cowl, with the result that it will assist in producing the updraft through the conduit 1, which withdraws the foul, vitiated, or heated air from the apartment or apartments with which the conduit 1 communicates.

It is thought the many advantages of my improved ship's cowl can be readily understood from the foregoing description, taken in connection with the accompanying drawings, and it will, furthermore, be evident that changes, variations, and modifications can be resorted 60 to without departing from the spirit of the invention or sacrificing any of its advantages, and I therefore do not wish to restrict myself to the details of construction hereinbefore described and as shown in the accompanying 65 drawings, but reserve the right to make such changes, variations, and modifications as come properly within the scope of the protection 70 prayed.

Having thus fully described my invention, 75 what I claim as new, and desire to secure by Letters Patent, is—

1. A ship's cowl comprising an upper section forming a mouth portion, and a collar surrounding and connected to the upper end 80 of said upper section, said collar gradually increasing in width upwardly, said collar projecting inwardly at an inclination, the inclination of the upper portion of the collar being greater than the lower portion, the upper portion of the said collar projecting over the mouth of said upper section, said collar further projecting away from the mouth of said upper section and said collar in connection with said upper section forming an air-passage 85 for deflecting the air across the mouth of said upper section.

2. A ship's cowl comprising an upper section forming a mouth portion, a collar surrounding and connected to the upper end of 95 said upper section, said collar gradually increasing in width upwardly, said collar projecting inwardly at an inclination, the inclination of the upper portion of the collar being greater than the lower portion, the upper portion of the said collar projecting over the mouth of said upper section, said collar further projecting away from the mouth of said upper section and said collar in connection with said upper section forming an air-passage 100 for deflecting the air across the mouth of said upper section, and a plurality of short rods secured to the upper section near the upper end thereof and through the inner face of the collar near one end thereof, said rods adapted 105 to connect the collar to the upper section.

In testimony whereof I have hereunto set my hand in presence of two subscribing witnesses.

CHARLES A. WITHERS.
